UNITED STATES PATENT OFFICE

ROBERT WHYTE, OF LANSING, MICHIGAN, ASSIGNOR TO GENERAL MOTORS CORPORATION, OF DETROIT, MICHIGAN, A CORPORATION OF DELAWARE

OIL FILTER INSTALLATION

Application filed June 15, 1928. Serial No. 285,620.

This invention relates to the mounting of oil filters and has particular reference to a filter and the mounting thereof as applied to internal combustion engines used on automotive vehicles.

Prior constructions have made use of a can or container in which a filtering unit has been mounted. This container is usually secured to or positioned at the dashboard or cowl pan 10 and the oil led to and conducted therefrom by means of a system of piping suitably connected with the force feed system of the internal combustion engine. This piping is objectional for the reason that it renders the 15 engine less accessible and the system liable to be damaged or broken and adds to the cost of the lubricating system.

It is the object of the present invention to eliminate the container and all piping and to 20 apply the filtering unit to the engine where it will be out of the way and rendered more accessible and readily replaced.

The object of the invention is accomplished by casting a suitable housing integral with 25 the cylinder block preferably at the rear end thereof. This housing is cast at one of the cam shaft bearings and allows for the use of the conventional spiral bag type of filtering unit. The end of the filtering medium or unit 30 is attached to the engine block at the bearing and by means of suitable metered drilled passages the oil is delivered from the force feed system through the bearing to the filtering unit. The oil flows from the unit and drips 35 into the housing from where it is returned to the crank case past a suitable test valve.

The housing is preferably inclined upwardly from the bearing although it may be downwardly inclined if so desired. While the 40 drawings show the invention applied to the rear end of the engine block where it is out of the way of the fan and water pump it is nevertheless within the scope of the invention to cast the housing at the front of the block 45 or at an intermediate portion thereof.

Referring to the drawings:

Figure 1 shows an elevational side view of the end portion of a V-type internal combustion engine showing the invention applied thereto.

Figure 2 is a section on the line 2—2 of Figure 1.

Referring to the drawings:

The numeral 10 indicates a V-type internal combustion engine having the two banks 55 of cylinders 12 and 14, the engine block is indicated at 16, and cast integral with the block preferably at the rear end is the housing 18. The inner end 20 of the housing is positioned at a bearing 22 of the cam shaft 60 24 while the outer end 26 of the housing is substantially in line with the end of the bank 12 of the cylinders.

The housing 18 has the removable cover 28 secured thereon by means of a screw 30 fastened to a stud or projection 32 on the end of the filtering unit 34. The filtering unit 34 is of the conventional spiral bag type such as shown in McKinley, 1,651,400.

The inner end of the filtering unit 34 has 70 a screw-threaded extension 36 which is screwed into an opening 38 in the bottom 20 of the housing and which opening 38 communicates at intervals through an opening 40 in the bearing 22 with a three-armed passage 42 in the cam shaft 24.

The crank case of the engine block 16 is indicated at 44 while 46 designates the oil pan. Secured to the crank case and positioned within the oil pan is the usual force 86 feed oil pump 48 which takes the oil from the oil pan 46 through the pipe 50 and forces it into the manifold pipe 52 through suitable passages 54 to the crank shaft bearings 60. An annular groove 56 in the crank 85 shaft 58 (or in one of the crank shaft bearings 60) leads the oil to a passage 62 in a rib 64 in the crank case. From the passage 62 the oil is delivered to the three-armed 90 passage 42 in the cam shaft 24 and during each rotation of the cam shaft three shots of oil will be delivered to the filter from the various arms of the passage 42. The oil will be forced through the central passage 95 in the oil filter and will drip from the outer side of the filtering material as indicated by the arrows 66 to the bottom 68 of the housing 18. From the bottom 68 the oil will flow, as indicated by the arrows 70, through 100

an opening 72 in the housing and drain back to the oil pan 46.

Positioned in an opening 74 in the bottom of the housing 18 and at the opening 72 is 5 a test valve 76 of the conventional type the purpose of which is to ascertain whether the filter is functioning. By unscrewing the thumb screw handle 78 the test valve will be opened and if oil is flowing from the end 10 thereof it will show that the filter is working. If no oil flow is observed it will show that the filter is clogged.

I claim:

- 15 1. In combination with an internal combustion engine having a camshaft, a housing secured to the engine having one end terminating at a camshaft bearing, an oil filter mounted in said housing and having direct oil inlet communication with said bearing.
- 20 2. In combination with an internal combustion engine having a shaft having a bearing, a housing integrally formed with said engine and having an opening at one end communicating with said bearing, and an oil filter secured in said housing and having one end connected to said opening.

In testimony whereof I affix my signature.
ROBERT WHYTE.
